UNITED STATES PATENT OFFICE.

JOHN D. CHESNUT AND HARRIS A. RAY, OF OAKLAND, AND CHARLES H. WARFIELD,
OF SAN FRANCISCO, CALIFORNIA.

NEWSPAPER-VENDING MACHINE.

Application filed March 26, 1923. Serial No. 627,838.

This invention relates to a vending machine and especially to that type employed for selling newspapers, magazines and the like, and it more particularly seeks to provide a machine of this type adapted for use in public places such as depots, suburban railway stations, hotels and in other places.

The object of the present invention is to generally improve and simplify machines of this character; to provide a machine which will support newspapers on edge and in a position to be seen by the purchaser; a machine which is adapted to quickly and readily release a paper upon the insertion of a coin and actuation of the mechanism controlled thereby; a machine which may be readily and quickly loaded or refilled by an authorized person; a machine provided with a novel feeding and releasing mechanism, which is automatically adjustable to papers of various lengths, thicknesses, etc., for instance, the ordinary weekly form or the heavy Sunday edition, and which serves the important function of preventing the delivery of more than one newspaper at a time; and further to provide a coin controlled actuating mechanism which may be set to make one charge for ordinary daily editions and another charge for the heavy Sunday editions. Other objects will hereinafter appear.

One form which our invention may assume is exemplified in the following description and illustrated in the accompanying drawings, in which—

Fig. 1 is a front view of the machine partly broken away to show the interior mechanism.

Fig. 2 is a plan view in section taken on line 2—2, Fig. 1.

Fig. 3 is a vertical cross section taken on line 3—3 Fig. 1.

Fig. 4 is a view similar to Fig. 3, it showing the paper discharging mechanism in an elevated position.

Fig. 5 is a side elevation of the coin controlled actuating mechanism.

Fig. 6 is a view similar to Fig. 5, but showing the coin controlled actuating mechanism in its forward or releasing position.

Fig. 7 is a detail end view of the coin controlled actuating mechanism.

Referring to the drawings in detail, and particularly to Figs. 1, 2, 3, and 4, A in-

dicates in general a housing interior of 55 which is mounted a mechanism for discharging the newspapers; this mechanism being divided into two groups, to wit, a newspaper supporting, feeding and discharging mechanism, and a coin controlled mechanism 60 whereby said first mechanism is actuated. The first group of mechanism is generally indicated at B and the second group at C. The first group of mechanism is supported by a base or frame generally indicated at 2. 65 This base is secured to the bottom section of the casing in any suitable manner and it carries a main actuating shaft 3, which extends longitudinally through the frame and is suitably journaled therein. Secured on 70 each end of the shaft is a crank arm 4, and pivotally connected to the outer end of each crank arm 4 is a second arm 5. These arms are connected by a feeder bar 6, in the forward face of which is formed a series of 75 prongs 7. A frictional joint is formed as at 8 between the arms 4 and 5 and means are employed for limiting the movement of the arms 5 when they are being lowered as will hereinafter be described; the means for 80 limiting said movement being in this instance a pair of chains or flexible cords such as shown at 9; these cords being secured at their outer ends to pins 10 carried by the respective arms 5, and at their inner ends to 85 lugs 11 carried by the main frame.

The shaft 3 is turned by the coin controlled actuating mechanism C in one direction and it is returned automatically when released thereby by means of a pair of springs 90 12, one disposed at each end of the main frame as shown in Fig. 2. These springs are secured at their rear ends to the sides of the main frame and at their forward ends to crank arms 13 secured to the main actuating shaft 3. Formed above the base or main frame and supported thereby is a pair of supporting tracks 14. Slidably mounted on these tracks and guided thereby is a pusher plate 15, and disposed at the extreme forward end of the tracks or supports 14 is a stop plate 16. This plate extends across the entire front of the main supporting frame and is in actual practice slightly longer than the newspapers or other articles to be dispensed.

The machine is in this instance described as a newspaper vending machine and the

newspapers to be vended are generally indicated at E. Their forward movement is limited by the stop plate 16 which is disposed at the lower end of the papers, and their forward movement is further limited by an upper finger 17 which is centrally disposed with relation to the supporting frame and the tracks 14. Means are employed for automatically advancing the papers and the pusher plate 15 as the papers are discharged or dispensed. This means embodies an arm 18 pivotally supported near the rear of the machine and at one end thereof as indicated at 19. The forward end of this arm is connected with the center portion of the pusher plate 15 as indicated at 20 and it is slotted as at 21 to permit a straight forward movement of the pusher plate and at a circular movement of the arm 18. The arm 18, together with the pusher plate connected therewith, is propelled in a forward direction by means of a series of springs 22, 23 and 24. These springs are gradually placed under tension when the pusher plate and arm 18 are moved back to the dotted line position indicated at 18^a, and they gradually release their tension as the arm 18 and the pusher plate move in a forward direction. The spring 24 is first placed under tension; secondly, the spring 23, and last the spring 22. When the machine is being loaded and a new stack of papers is inserted, it is obvious that the load is heaviest and forward resistance of the entire stack of papers is the greatest. For this reason all three springs are placed under tension at this time, however, as the papers are dispensed and forward movement takes place, spring 22 will first release, secondly spring 23, and the final work will then be accomplished through means of the spring 24.

The casing is provided with a door F, which may be unlocked by an authorized person when the machine is to be loaded. It is, therefore, only necessary to insert a key and to release the door when it is desired to load the machine, and then to force the pusher plate back into the dotted line position shown at 18^a in Fig. 2. The plate is here temporarily locked against forward movement by means of a latch 25 during the loading operation. The inner end of this latch engages the arm 18 and secures it against forward movement. The papers may then be placed forward of the pusher plate 15 until the entire space between said plate and the front stop plate 16 is filled. Latch 25 is then released by lifting upwardly on the forward end thereof as indicated at 26 and arm 18 and pusher plate 15 are thus free to move in a forward direction so as to maintain the foremost paper in snug engagement with the stop plate 16 and the finger 17. The door is now closed and locked and when this is accomplished

the machine is ready for operation. The machine may be operated by any one by the mere insertion of a proper coin and by depressing the main operating lever generally indicated at G. During forward movement of this lever, a turning movement is imparted to the main operating shaft 3 in the direction of arrow b, see Figs. 3 and 4, and as the crank arms 4 are rigidly secured to the shaft it is obvious that they will turn in unison with the same. The arms 5, as previously stated, are pivotally secured to the outer ends of the arms 4 and as the pivotal connection frictionally secures the arms 5 against movement, it is further obvious that they will swing the feeder bar 6 upwardly against the foremost paper to a point where the arms 5 and the feeder bar 6 will assume the dotted line position indicated at 6^a. The frictional resistance in the pivotal connections or joints indicated at 8 is sufficient to force the prongs into the foremost section of the paper and positive engagement is thus made which will cause the paper to move in an upward direction, as shown in Fig. 4, during further turning movement of the main operating shaft 3; the total distance or movement imparted being that shown by the two positions indicated at 30 and 31, see Fig. 4. The lowermost position is that assumed at 30 and the uppermost position is that shown at 31, the point where actual engagement is made with the foremost paper, or where the prongs first enter, being indicated at 6^a. When a paper has been elevated to the position shown in Fig. 4, at the end of the turning movement of shaft 3, shaft 3 is suddenly released and it is almost instantaneously returned due to the pull of the springs 12 on the crank arms 13. The prongs 7 will during this quick return movement be withdrawn from the paper and the paper will drop by gravity in a downward direction and during this drop it will strike the forward inclined face of the stop plate 16, which inclined face is indicated at 16^a, see Fig. 4, and it will then strike a pair of curved guides or ribs 16^b which form a part of the base or main frame. These guides direct the paper to an exit opening or slot 32 and the paper is thus discharged.

The coin actuating mechanism is the means relied upon for imparting a turning movement to the shaft 3 and for suddenly releasing the same when the paper to be discharged has been raised to its uppermost position. A brief description of the coin actuating mechanism will, therefore, be given:

The coin actuating mechanism is perhaps best illustrated in Figs. 5, 6 and 7. It consists of an arm 40 which is secured to the shaft 3 in any suitable manner. It secondly embodies a sleeve turnably mounted on the shaft as indicated at 41 in Fig. 7 and the

main operating lever G, which in turn is secured to the sleeve. Secured to the inner end of the sleeve and turnable in unison with the sleeve and the main operating lever G 5 is an arm 42, and secured to the outer end of said arm are two interspaced plates as indicated at 43 and 44. These plates are spaced apart to form two slots as indicated at 45 and 46, and these slots align with separated slots formed in a coin chute generally indicated at 47. One slot is of a size to receive five cent pieces and the other slot is of a size to receive ten cent pieces. The openings communicating with the slots and 10 through which the coins are inserted are indicated at 48, see Fig. 1. Disposed behind the plate in which the openings 48 are disposed is a sliding plate 49, see Fig. 2. This plate has two slots formed therein as indicated at 50 and 51. When the plate 40 assumes the position shown in Fig. 2, slot 50 registers with the slot through which the five cent pieces are inserted and the ten cent slot is at the same time closed. However, by 15 sliding the plate 49 in the direction of arrow c, see Fig. 2, the five cent slot is closed and register is made between the ten cent slot and the slot 51. In other words the coin controlled actuating mechanism is so constructed that it may be operated either by a five cent piece or a ten cent piece. This is of considerable importance as it permits an extra charge to be made for the heavy editions, such as are issued on Sundays and 20 holidays, and a smaller price to be charged for the ordinary daily editions of the papers. The plate 49 is controlled by the operator or other authorized person having charge of the machine, and it is therefore set by him 25 either to receive a five or ten cent piece as occasion may demand. A five cent piece when inserted falls down through the coin chute 47 and enters the space 45 formed between the lever 42 and the plate 43. A ten cent piece falling through the coin receiving chute 47 will enter the space 46 formed between the plates 43 and 44. Either coin serves the function desired and the operation of the mechanism is the same 30 whether one coin or the other is inserted.

The arm 40 which is secured to the main operating shaft 3 is disposed below the plates 43 and 44 and as such forms a stop which arrests further downward movement 35 of the coin when deposited between the plates. The upper end of the arm 40 is extended to cover both the spaces indicated at 45 and 46 and therefore serves as a stop in either case, that is whether a five cent piece or a ten cent piece is inserted. Pivotally mounted on one side of the arm 42, as indicated at 52, is a Y-shaped arm generally indicated at 53. This arm carries a lug or finger 54 which aligns with the spaces indicated at 45 and 46, and as such forms a

stop at the rear of the arm 42 which prevents the coin from falling out in that direction. With the coin inserted it is only necessary to swing the lever G in a forward direction, or that indicated by the arrow d. 40 The coin inserted will during this movement form a lock between the arm 40 and the arm 42 and the two will therefore swing in unison until the dotted line position indicated at 60, see Fig. 5, is assumed. At this point 45 the coin is released and rolls out in the direction indicated by the dotted line shown at 61, see Fig. 5. The coin is here released due to a rocking movement which is imparted to the Y-shaped lever 53, said rocking movement being imparted when one end of the lever or that indicated at 62 rides over a pin indicated at 63. This rocking movement also causes the opposite end of the Y-shaped lever or that indicated at 64 50 to enter the outer end of the arm 40, which is notched for the reception thereof, and a lock is thus formed between the lever 53 and the arm 40. Further movement after the coin is released will thus take place as 55 arm G is moved until it engages a stop pin 65. At this point a third extension on the Y-shaped lever or that indicated at 66 strikes a stop 67 and a rocking movement is thus imparted to the Y-shaped lever which 60 pulls the locking member 64 carried thereby out of engagement with the notched end of the arm 40. The arm 40 is thus released and as it is secured to the main operating shaft, it can readily be seen that the operating shaft will be almost instantaneously returned to normal position due to the pull exerted by the springs 12 on the crank arms 13; the return movement of the shaft being limited and being also cushioned when the outer ends of the crank arms 4 strike buffers or springs indicated at 70, see Figs. 3 and 4; the return position of the arm 40 being shown and indicated at 40 in Fig. 6, and the return position of shaft 3 and arms 4 65 and 5 being shown by full lines in Fig. 3.

The coin controlled actuating mechanism will not operate unless a proper coin is inserted. If the coin is too large, it simply will not enter. If it is too small, it passes through and no action will take place. If a coin is not inserted, and even though the lever G be pushed to its forward position indicated in Fig. 6, no lock will be formed between the arm 40 and the lever or arm 42; that is, simultaneous movement of the arms 40 and 42 will only take place when a coin is interposed between the upper end of the arm 40 and the lug 54 which is carried by the Y-shaped arm 53. The arm 42, 115 together with the Y-shaped lever carried thereby and also the main operating lever, is returned to the full line position shown in Fig. 5 after arm 40 is released either manually or automatically; that is, the person 120

operating the machine may pull the lever G back or he may leave the lever in engagement with the stop 65. If he should do so, the levers would be returned to normal position by means of a spring generally indicated at 80.

A rather specific form of coin controlled actuating mechanism has here been described. We, however, wish it understood that any other suitable form of coin controlled mechanism may be employed as we do not wish to limit ourselves to the type here illustrated. The only essential mechanism required would be a coin controlled mechanism which is capable of imparting a turning movement to the shaft 3, and which will release the shaft 3 when it has been turned a predetermined distance. We further wish it understood that various changes in the construction and arrangement of the several parts herein shown and described may be resorted to within the scope of the appended claims; similarly, that the materials and finish of the several parts employed may be such as the experience and judgment of the manufacturer may dictate or various uses may demand.

Having thus described our invention, what we claim and desire to secure by Letters Patent is—

1. In a machine of the character described a support adapted to receive a plurality of papers on end, a stop forward of the support engageable with the foremost paper, a pusher plate engaging the rearmost paper and adapted to advance the papers towards the stop as they are discharged one by one, and means for automatically advancing the pusher plate, said means comprising an arm pivotally supported at one end and positioned so that its free end engages the center portion of the pusher plate, and a plurality of springs of different length connected to the arm, all of said springs exerting a tension to swing the arm and the plate forwardly when the plate and arm are retracted, and each spring automatically and successively releasing its tension as the arm and plate advance.

2. In a machine of the character described a support adapted to receive a plurality of papers on end, a stop forward of the support engageable with the foremost paper, a pusher plate engaging the rearmost paper and adapted to advance the papers towards the stop as they are discharged one by one, and means for automatically advancing the pusher plate, said means comprising an arm pivotally supported at one end and positioned so that its free end engages the center portion of the pusher plate, and a plurality of springs connected to the arm at points intermediate the pivot and the free end, said springs being of decreasing length and releasing

their pull on the arm one after the other as the arm swings forwardly and the pusher plate advances.

3. In a machine of the character described, a casing, a support within the casing adapted to receive a plurality of papers on end, a stop member on the forward end of the support engaging the lower edge of the foremost paper, means for automatically advancing the papers against the stop and for maintaining the foremost paper in engagement therewith, a main actuating shaft extending longitudinally of the frame and journaled therein, a pair of crank arms one on each end of the shaft, a pair of arms pivotally secured on the outer end of each crank arm, means maintaining the last named arms and the crank arms in frictional engagement to produce a friction joint, a feeder bar connecting the outer ends of the last named arms, a series of prongs carried by the feeder bar, means for imparting a partial rotary movement to the main actuating shaft to elevate the crank arms, the second named arms and the feeder bar, and to swing the feeder bar and the prongs carried thereby inwardly into engagement with the foremost paper and to raise the foremost paper above the stop, and means for quickly reversing the movement of the shaft to quickly retract the feeder bar and the prongs to release the paper and to permit discharge thereof.

4. In a machine of the character described, a casing, a support within the casing adapted to receive a plurality of papers on end, a stop member on the forward end of the support engaging the lower edge of the foremost paper, means for automatically advancing the papers against the stop and for maintaining the foremost paper in engagement therewith, a main actuating shaft extending longitudinally of the frame and journaled therein, a pair of arms one on each end of the shaft, a pair of arms pivotally secured on the outer end of each crank arm, means maintaining the last named arms and the crank arms in frictional engagement to produce a friction joint, a feeder bar connecting the outer ends of the last named arms, a series of prongs carried by the feeder bar, means for imparting a partial rotary movement to the main actuating shaft to elevate the crank arms, the second named arms and the feeder bar, and to swing the feeder bar and the prongs carried thereby inwardly into engagement with the foremost paper and to raise the foremost paper above the stop, means for quickly reversing the movement of the shaft to quickly retract the feeder bar and the prongs to release the paper and to permit discharge thereof, and a flexible connection between each end of the feeder bar and the frame,

5. In a machine of the character described, a support adapted to receive a plurality of papers on end, a stop forward of the support engageable with the foremost paper, means for automatically advancing the papers against the stop and for maintaining the foremost paper in engagement therewith, a main actuating shaft extending longitudinally of the stop member and disposed below the same, a pair of crank arms secured to the shaft one at each end thereof, a pair of links pivotally mounted on the outer ends of said cranks, a rod connecting said links, pins in one face of said rod, a pair of cords secured at one end to the links and at their opposite end to a stationary support, manually actuated means for imparting the rotary motion to the main actuating shaft which will lift the links and the rod carried thereby upwardly, said cords during said upward movement pulling the links and the rod inwardly so that the pins carried by the rod will engage the foremost paper and lift it upwardly to above the stop, and means for automatically releasing the main actuating shaft when it has turned a predetermined portion of a revolution and for rapidly returning the shaft so as to release the paper and to permit it to drop by gravity.
